The ornamental design for a combined water dispenser and filter, as shown and described.

DESCRIPTION

FIG. 1 is a front view of a combined water dispenser and filter showing my design;

FIG. 2 is a right side view thereof;

FIG. 3 is a bottom view thereof;

FIG. 4 is a partial bottom, front perspective view thereof;

FIG. 5 is a top view thereof;

FIG. 6 is a top and front perspective view thereof;

FIG. 7 is a rear view thereof; and,

FIG. 8 is a right side view thereof.

FIG. 1

FIG. 2

FIG. 3

FIG. 4

FIG. 5

FIG. 6

FIG. 7

FIG. 8
